UNITED STATES PATENT OFFICE.

JOHN A. LUNDEN, OF CHICAGO, ILLINOIS, ASSIGNOR TO LAKESIDE SUPPLY COMPANY, OF CHICAGO, ILLINOIS, A CORPORATION OF ILLINOIS.

SPRING MOTOR.

Application filed September 21, 1923. Serial No. 663,932.

To all whom it may concern:

Be it known that I, JOHN A. LUNDEN, a citizen of the United States, residing at Chicago, in the county of Cook and State of Illinois, have invented a certain new and useful Improvement in Spring Motors, of which the following is a full, clear, concise, and exact description.

My invention relates to spring motors and has for its general object, the simplification in construction and improvement of operation of such motors.

The motor of my invention comprises a coiled spring, a winding element with which one end of the spring is assembled, a rotatable load operating element with which the other end of the spring is assembled, and a mounting upon which said spring, the winding and the load operating element turn together bodily.

In the preferred embodiment of the invention, the winding element is in the form of a spur gear with which the inner end of the spring is connected. This spur gear is in mesh with a spur pinion that is normally stationary whereby the spur gear turns upon the pinion as upon a track as the spring unwinds. The load operating element is preferably in the form of a spur gear in mesh with a pinion of a load operating gear train and co-axial with the aforesaid normally stationary pinion.

A detent permits the winding element to be turned in a winding direction, but prevents reverse movement of this element.

The invention will be more fully explained by reference to the accompanying drawing illustrating the preferred embodiment thereof and in which Fig. 1, is a plan view of a motor as it is preferably constructed, taken on line 1—1 of Fig. 3. Fig. 2 is a sectional view on line 2—2 of Fig. 1; Fig. 3 is a side view taken on line 3—3 of Fig. 1, a mounting for the motor and one form of load being also illustrated; and Fig. 4 is a sectional view on line 4—4 Fig. 1 with the motor mounting and load shown in Fig. 3 added.

Like parts are indicated by similar characters of reference throughout the different figures.

The motor illustrated includes two similar motive units, similar characters of reference being applied to similar parts of these units.

Each motive unit includes a spring formed

anchored at its inner end to shaft 2 by a screw 3 and at its outer end to a casing 4 by a rivet 5. The casing is common to both motive units and is arranged to turn upon the axis of a normally stationary pinion 6 that is centrally disposed between both motive units. The shaft 2 of each motive unit has a spur gear 7 fixed thereon, both spur gears being in mesh with the pinion 6 and capable of travel thereon, as upon a track. When the springs are permitted to unwind, turning movement is forced thereby of the casing 4.

The casing 4 is caused to operate the load. In the instance shown the casing performs this function through the intermediation of a spur gear 8 co-axial with the normally stationary pinion 6. Spur gear 8 is in mesh with a pinion 9 that is fixed with respect to and is co-axial with the spur gear 10, meshing in turn, with a spur pinion 11. The latter pinion is fixed upon an upright load shaft 12, here illustrated as the driving spindle of a phonograph turn table 13. The speed of rotation of the turn table may be governed by some suitable governor, such as that illustrated at 13' which is driven from the spindle by the gearing 14.

The pinion 6 is normally held from rotation by a detent 15 engageable with a detent wheel 16 fixed upon a shaft 17 that carries a bevel pinion 18 which is in mesh with a bevel pinion 19 that is fixed with respect to the pinion 6. The shaft 17 has an angular continuation 20 which carries a handle 21.

The detent permits the shaft to be turned clockwise, but prevents reverse movement. When the shaft is turned clockwise the pinion 6 is turned to rotate the spring winding gears 7.

While I have herein shown and particularly described the preferred embodiment of my invention, changes may be made without departing from the spirit of my invention.

Having thus described my invention I claim as new and desire to secure by Letters Patent the following:

1. The combination with a coiled spring; of a winding gear element with which one end of the spring is assembled; a rotatable load operating element with which the other end of the spring is assembled; a second winding gear element in mesh with the aforesaid winding gear element; a winding shaft

105

110

in driving relation to the second winding gear element; a mounting upon which said spring, the first aforesaid winding gear element, and the load operating element turn together bodily; and a detent associated with the winding shaft permitting rotation of said shaft in a winding direction and preventing reverse rotation of the shaft.

2. The combination with coiled spring; 10 of a winding gear element with which one end of a spring is assembled; a rotatable load operating element with which the other end of the spring is assembled; a second winding gear element in mesh with the aforesaid winding gear element; means for turning the second winding gear element in a winding direction; a mounting affording an axis of rotation for said spring, the first aforesaid winding gear element and the 20 load operating element that is coincident with the axis of the second aforesaid winding gear element; and a detent associated with the second aforesaid winding gear element permitting rotation thereof in a winding direction and preventing reverse rotation thereof.

3. The combination with a coiled spring; 30 of a winding gear element with which one end of the spring is assembled; a rotatable load operating element with which the other end of the spring is assembled; a second winding gear element in mesh with the aforesaid winding gear element; and with which the load operating element is co-axial; 35 means for turning the second winding gear element in a winding direction; a mounting affording an axis of rotation for said spring, the first aforesaid winding gear element and the load operating element that is coinci-

dent with the axle of the second aforesaid 40 winding gear element; and a detent associated with the second aforesaid winding gear element permitting rotation thereof in a winding direction and preventing reverse rotation thereof.

4. The combination with a coiled spring; 45 of a winding gear element with which one end of the spring is assembled; a rotatable load operating element with which the other end of the spring is assembled; a second winding gear element in mesh with the aforesaid winding gear element; means for turning the second winding gear element in a winding direction; and a mounting affording an 50 axis of rotation for said spring, the first aforesaid winding gear element and the load operating element that is coincident with the axis of the second aforesaid winding gear element.

5. The combination with a coiled spring; 55 of a winding gear element with which one end of the spring is assembled; a rotatable load operating element with which the other end of the spring is assembled; a second winding gear element in mesh with the aforesaid winding gear element; and with 60 which the load operating element is co-axial; means for turning the second winding gear element in a winding direction; and a mounting affording an axis of rotation for 65 said spring, the first aforesaid winding gear element and the load operating element that is coincident with the axis of the second aforesaid winding gear element.

In witness whereof, I hereunto subscribe 70 my name this 14th day of September A. D., 1923.

JOHN A. LUNDEN.
